Primary Examiner — Daniel J Domino*Assistant Examiner* — Samina Vieth(74) *Attorney, Agent, or Firm* — Frank Niranjan**CLAIM**

The ornamental design for a ring remote control as shown and described.

DESCRIPTION

FIG. 1 is a top, front, right side perspective view of a ring remote control showing my new design;

FIG. 2 is a bottom, rear, left side perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines depict portions of the article and form no part of the claimed design.

1 Claim, 8 Drawing Sheets(56)
